Attorney

UNITED STATES PATENT OFFICE.

WILFRID DORION, OF CHARLESBOURG, QUEBEC, CANADA.

CHANGE-SPEED DEVICE.

1,318,733.

Specification of Letters Patent.

Patented Oct. 14, 1919.

Application filed April 11, 1918. Serial No. 227,939.

To all whom it may concern:

Be it known that I, WILFRID DORION, residing at Gros Pin, Charlesbourg, in the Province of Quebec, in the Dominion of Canada, have invented certain new and useful Improvements in Change-Speed Devices; and I do hereby declare that the following is a full, clear, and exact description of the same.

10 This invention relates to improvements in change-speed devices for driving pulleys, and is here shown as applied to a motor cycle.

15 The invention consists particularly of two members or pulleys of different diameter, the larger one being adapted to fit over the pulley of smaller diameter and so enlarge its diameter, thereby reducing the speed.

20 The object of the invention is to provide a simple, efficient and comparatively inexpensive device of the character above indicated.

25 The invention will hereinafter be fully explained in the following description, and its preferred embodiment is illustrated in the accompanying drawings in which:

Figure 1 is a side elevation of the invention here shown as applied to a motor cycle.

30 Fig. 2 is an enlarged front elevation of the invention and its operating mechanism, disclosing portions of the motor and of the top bar of the frame of the motor cycle.

Fig. 3 is an enlarged side elevation of the invention.

35 Fig. 4 is a side elevation of the driving pulley.

Fig. 5 is a front elevation of Fig. 4.

Fig. 6 is a side elevation of the large diameter pulley.

40 Fig. 7 is a front elevation of Fig. 6.

Like numerals of reference indicate corresponding parts in each figure.

In the drawings, 1 is the cycle, 2 the motor and 3 the crank shaft. On the end of said crank shaft 3 is rigidly mounted the pulley 4 which is provided with the side flanges or guides 5 and 6 having the inclined sides 7; and 8 are slots or openings in which the larger diameter pulley 9 slides.

50 The pulley 9 has a drum-like shape, and 10 are lateral slots provided therein which divide its periphery into separate, transversely-disposed sections or tongues; 11 are

oblique lugs which project radially from the free edges of said pulley sections or tongues 55 and extend toward the axis of the pulley which are adapted to slide and support the pulley 9 over the pulley 4. The arrangement of the aforesaid pulley sections or tongues and their lugs 11 correspond to that 60 of the slots 8 in pulley 4, so that the pulley 9 will fit within the pulley 4 as disclosed in dotted lines in Fig. 2. The outer end of the hub end of said pulley 9 is provided with a circular groove 12 in which fits the sleeve 65 13, and 14 is a forked rod pivotally engaging said sleeve.

A bracket 15 is secured on said motor 2 and projects outward, and on its outer end the bell-crank lever 14 is pivotally secured 70 thereto. On the end of the upper arm of said lever 14 is pivotally secured the link 16, and 17 is a hand lever pivoted at 18 to the frame of the cycle, or in some other manner if preferred, and pivotally secured 75 at its outer end to the link 16. On the frame of the cycle is provided a bracket 19 suitably notched to lock the said lever in one or the other position.

A belt-tightening lever 20 of bell-crank 80 form is suitably pivoted adjacent the lower end of its vertical arm to the frame of the cycle, and 22 is a toothed rack adapted to engage the said vertical arm of said lever and lock it in position; and on the free rear 85 end of the lower or horizontal arm of said lever is mounted the roller 23 which is adapted to take up the slack in the belt 24 which engages the driving pulley 4 and the pulley 25 secured to the rear wheel of the 90 cycle.

It will readily be seen that in the operation of the device, if the hand lever 17 is pulled from left to right, the bell-crank lever 14 will be actuated and will push the pulley 9 into the position shown in dotted lines in Fig. 2, thus enlarging the diameter of the pulley 4 and thereby reducing the speed. When the lever 17 is swung in the opposite direction, it will cause the pulley 9 to be disengaged from the pulley 4, thus reducing its diameter. The slack which will occur in the belt 24 will be taken up by the lever 20, by pushing it downwardly.

It is evident from the foregoing description that any other suitable means of operat-

ing the pulley 9, may be used without departing from the scope and field of the invention as hereinafter claimed.

What I claim as my invention is:

- 5 1. A device of the character described, comprising a shaft; a flanged driving pulley mounted thereon and having oppositely-located guide slots formed through its flanges; a pulley of larger diameter, slidably mounted on said shaft adjacent said driving pulley and provided with lugs registering with the slots in said driving pulley; and means to slide the pulley of larger diameter toward the driving pulley so as to cause said lugs 10 to pass through said guide slots and said pulley of larger diameter to fit over said driving pulley and thereby enlarge its diameter; substantially as described.
- 15 2. A device of the character described, comprising a shaft; a flanged driving pulley mounted thereon and having a plurality of oppositely-located guideslots formed through its flanges; a pulley of larger diameter slidably mounted on said shaft adjacent

said driving pulley and having its peripheral wall split into a plurality of spaced, transverse sections or tongues which are provided on their free edges with inclined lugs, said sections or tongues and their lugs registering with the slots in said driving pulley; 25 a member for shifting one of said pulleys toward the other so as to cause said lugs and pulley sections or tongues to pass through said guide slots, and said sections or tongues to surround said driving pulley 30 and thereby enlarge its diameter, said shifting member being connected at one end to the pulley to be shifted; and an operating member for said shifting member connected to the other end thereof; substantially as de- 35 40 scribed.

Signed at Quebec, Canada, this 16th day of October, 1917.

WILFRID DORION.
